United States Patent

Des. 238,658
Patented Feb. 3, 1976

238,658

DEVELOPER POWDER CONTAINER

Stanford C. Stone, South St. Paul, Minn., assignor to
Minnesota Mining and Manufacturing Company

Filed Dec. 7, 1973, Ser. No. 422,885

Term of patent 14 years

Int. Cl. D9—03

U.S. Cl. D9—210

FIG. 1

FIG. 2

FIG. 3

FIG. 4

FIG. 5

FIG. 6

FIG. 1 is a front perspective view of a developer powder container showing my new design;

FIG. 2 is a bottom plan view thereof;

FIG. 3 is a right side elevational view thereof, the side opposite being substantially a mirror image;

FIG. 4 is a top plan view thereof;

FIG. 5 is a rear elevational view thereof; and

FIG. 6 is a front elevational view thereof.

I claim:

The design for a developer powder container, as shown and described.
